UNITED STATES PATENT OFFICE

2,655,797

TIMER APPARATUS FOR PARKING METERS

Gerald A. Hale, Oklahoma City, Okla.

Application March 21, 1949, Serial No. 82,631

1 Claim. (Cl. 64—4)

1

This invention relates to a parking meter, and more particularly, but not by way of limitation to a timer mechanism which is releasably and detachably secured thereto. This application is related to the subject matter of applicant's co-pending application No. 619,477, filed October 1, 1945, and entitled "Automatic Parking Meter" now Patent No. 2,625,250 issued January 13, 1953.

It is an important object of this invention to releasably maintain an escapement timer assembly upon a parking meter frame plate and in operable relationship with the meter.

And still another object of this invention is to provide a drive mechanism for a parking meter having a removable and interchangeable escapement unit operably connected therewith.

And still another object of this invention is to provide a parking meter having frame plate constructed in such a manner to maintain a detachable escapement timer unit thereon, in such a manner to be operably cooperative with the drive assembly of the parking meter.

And still another object of this invention is to provide a parking meter having a separate timer unit which is releasable and detachable therefrom.

Other objects and advantages of the invention will be evident from the following detailed description, read in conjunction with the accompanying drawings, which illustrate my invention.

Referring to the drawings:

Fig. 1 is a back elevational view of a parking meter mechanism showing my improved invention thereon.

Fig. 2 is a fragmentary side elevational view of Fig. 1 with certain parts broken away for clarity.

Fig. 3 is a fragmentary perspective view of the back frame plate of the meter.

Fig. 4 is a perspective view from the rear of the escapement timer unit.

Fig. 5 is a detailed view of the timer shaft bearing.

Referring to the drawings in detail, reference character 2 designates a parking meter of the type disclosed and described in my co-pending application above referred to. The mechanism 2 comprises a back plate 4 cooperating with a front plate (not shown) for supporting the meter mechanism proper. A semi-circular dial 6 is supported by brackets 8 extending from the mechanism 2. The dial 6 cooperates with an indicator 10 in a manner as described in my co-pending application. A timer shaft 12 is loosely mounted in the frame plates and carries a suit-

2

able pinion gear 14 for driving the indicator sector gear 16. The driving means for the rotatable shaft 12 is provided through the clock works, timer, or escapement mechanism supported on the plate 4 in proximity of the loosely mounted shaft 12. The timer 18 is detachably secured to the plate 4 by a plurality of spaced locking studs 20 provided on the plate 4. The locking studs 20, as clearly shown in Fig. 3, are rigidly secured in any suitable manner (not shown) to the plate 4 and are each cut-away to provide a recessed portion 22 around a reduced stud 24 for a purpose as will be hereinafter set forth. The circumferential periphery of the timer housing 16 is provided with a plurality of circumferentially spaced outwardly extending flanges or projections 26. It will be apparent that the number of flanges is dependent upon the number of locking studs on the plate 4. In the present instance three studs and three flanges are preferably used, however, it will be understood that the invention is not limited to any particular number. The flanges are each provided with a cam surface 32 extending into a locking shoulder 34 for cooperation with the recesses 22 and stud 24 of the studs 20 as will be hereinafter set forth.

The timer 18 is preferably provided with a stub shaft 28 extending outwardly therefrom and cooperates with a freely rotatable bearing 30 disposed in the frame 4. The shaft 12 is also disposed in the bearing 30, thereby providing a sectional clock shaft, designated as 12 and 28, thereby permitting dis-engagement of the timer 18 without any removal of the pinion gear 14 and other elements of the parking meter which may be retained in the mechanism. The bearing 30 is provided with an irregularly shaped aperture 31 in order to conform to the irregularly shaped configuration of the shafts 12 and 28, thereby assuring rotation of the shaft 12 upon insertion of the timer driven stub shaft 28 in the loosely mounted bearing.

It will be apparent that in order to remove the timer 18 from the plate 4, it is only necessary to slightly rotate the timer 18 in a counter-clockwise rotation whereupon the cam faces 32 are dis-engaged from the slot recesses 24 of the retaining lugs 20. Furthermore, the stub shaft 28 of the clock 18 is removed from the bearing 30 and the timer 18 is completely removed from the meter mechanism.

A timer 18 may be replaced by disposing the cam surface 32 of the flanges 26 in the recess 24 of the plurality of spaced locking studs 20 with

a simultaneous insertion of the stub shaft 28 in the bearing 30 also journaling one end of the clock shaft 12. A right-hand movement of the timer 18 will effect a cam action on the surfaces 32 bringing the stop shoulders 34 into locking connection with the recesses 24 of the studs 20 thereby detachably locking the composite timer mechanism to the frame plate of the parking meter.

From the foregoing it will be apparent that the present invention provides a parking meter having a composite timer mechanism which is readily removed or detachable therefrom to permit interchangeability of timer units in a quick and efficient manner. This is particularly important in event the timer mechanism should become out of balance or inoperative for any reason, and it is desired to interchange a compact timer unit without necessarily dismantling the complete parking meter.

Changes may be made in the specification and drawings without departing from the spirit of the invention within the scope of the following claim, as set forth.

I claim:

An apparatus for coupling a driving unit having a drive shaft to a framed driven unit having a driven shaft, comprising a bearing member rotatably disposed in the frame of the driven unit, said bearing member having an aperture therein to receive the drive shaft and the driven shaft, whereby the bearing member will transmit rota-

5 tive movement of the drive shaft to the driven shaft, a plurality of outwardly extending circumferentially spaced flanges on the driving unit, the outer end surfaces of all of said flanges being substantially tangentially tapered in the same direction, and a plurality of studs secured to the frame of the driven unit circumferentially around said bearing member, said studs having recesses therein to receive said circumferentially spaced tapered flanges and secure the driving unit to the driven unit.

4 GERALD A. HALE.
